PLUMBING FIXTURE

John R. O'Brien, Long Island City, N. Y.

Application March 10, 1937, Serial No. 130,093

4 Claims. (Cl. 285—50)

This invention relates to improvements in plumbing fixtures.

One object of this invention is to provide an improved plumbing fixture in which a template is so constructed and employed that it will compel the plumber to have the pipe-terminals properly located with respect to one another as concerns their height, so that when the distributing-head is attached to the pipe-terminals, the distributing-head will be properly aligned with respect to the vertical and horizontal.

Another object of this invention is to provide an improved template which can be readily manufactured at minimum cost.

15 With the above and other objects in view, as will appear to those skilled in the art from the present disclosure, this invention includes all features in the said disclosure which are novel over the prior art.

20 In the accompanying drawings, in which one way of carrying out the invention is shown for illustrative purposes:

Fig. 1 is a front elevation of a plumbing fixture having a template and pipe-terminals secured thereto, illustrating one embodiment of the invention;

Fig. 2 is a rear elevation of a template and pipe-terminals, illustrating how the template necessitates the pipe-terminals being of proper 30 heights for proper assembly;

Fig. 3 is a plan view, partly in section, of the plumbing fixture illustrated in Fig. 1, with a distributing-head and nipples added thereto;

Fig. 4 is a rear perspective view of the template; and

Fig. 5 is a perspective view of one of the elbows.

In the description and claims, the various parts are identified by specific names for convenience, 40 but they are intended to be as generic in their application as the prior art will permit.

Referring to the drawings, 10 is a template, preferably of sheet-metal, having holes 11 formed therethrough, and non-circular sockets 12 pressed out. In the particular form of the invention illustrated, the non-circular sockets 12 are octagonal in form, the walls 13 of the octagonal sockets being flared outwardly (Figs. 2, 3 and 4) from the bottom 14 of the socket. Any suitable means, such as slots 15 and holes 16 are provided for the purpose of suitably attaching the template 10 to any suitable supporting-structure within a wall 17 (Fig. 3) in which 50 the template is to be used. The tubes or pipes

18, 19, 20 and 21 have their ends connected to pipe-terminals in the form of elbows 22, in the particular form of the invention illustrated in the drawings, each elbow 22 having an octagonal portion 23 adapted to properly fit or seat in any of the octagonal sockets 12 of the template. Each elbow also has a threaded portion 24 adapted to receive a nut 25 to draw the elbow up to proper position to seat its octagonal portion 23 in a socket 12 of the template.

10 Nipples 26 are secured to the elbows 21 and in turn lead into and are secured to a distributing-head or plural valve-structure 27 which may, for example, be a mixing-chamber for a shower and tub.

15 Inasmuch as the distributing-head 27 is an integral unitary structure having its lead-in openings of predetermined location and alignment, it is necessary for proper installation of the head 27 that the elbows on the ends of pipes 20 18 and 20 (Fig. 2) shall be exactly the same height, so that the head 27 shall occupy a proper position with respect to the vertical and horizontal, and that all of the pipes 18, 19, 20, 21 shall be of correct lengths so that their elbows 25 will be spaced on proper centers and at proper angles to correctly connect with the openings in the head 27.

20 By looking at Fig. 2, where the elbows 22 on the pipes 18 and 20 are at different heights, 30 it will be observed that their octagonal portions 23 do not correspond in position with the octagonal sockets 12 of the template and, therefore, it is impossible to seat the octagonal portions 23 of the elbows in the sockets. Thus, the 35 plumber is compelled to shorten pipe 18 or screw down the elbow thereon until the elbows come at the same height, whereupon the octagonal portions 23 of the elbows will properly seat in the octagonal sockets 12 of the template. 40 The pipes 18, 19, 20 and 21, ordinarily being of substantial length, can be readily sprung transversely sufficiently to bring them in proper position for securing in corresponding openings 14 of the template. Thus, it will be seen that the 45 template compels the plumber to have the elbows or whatever pipe-terminals are to be used, at proper heights, or else he will be unable to seat the octagonal portions of the elbows in 50 the octagonal sockets of the template.

When the nuts 25 are screwed on the threaded portions 24 of the elbows 22 firmly against the template 10, if the plumber has failed to have the ends of all the elbows 22 at right angles 55

to the template, any which are slightly off angle, as indicated in broken lines at 28 (Fig. 3) will be forced to ride down the flared walls 13 of the sockets 12 to bring end-faces 29 against the bottom-faces 14 of the sockets 12.

The invention may be carried out in other specific ways than that herein set forth without departing from the spirit and essential characteristics of the invention, and the present embodiment is, therefore, to be considered in all respects as illustrative and not restrictive, and all changes coming within the meaning and equivalency range of the appended claims are intended to be embraced therein.

15 I claim:

1. A template designed and adapted to be secured in a building wall or the like, said template having a plurality of template holes for pipe-members to extend therethrough, the portions of said template surrounding at least two of said holes being provided with non-circular sockets.

2. A template designed and adapted to be secured in a building wall or the like, said template having a plurality of template holes for pipe-members to extend therethrough, the portions of said template surrounding at least two of said holes being provided with flared and non-circular sockets.

of said holes being provided with flared and non-circular sockets.

3. A plumbing fixture comprising: a template designed and adapted to be secured in a building wall or the like, said template having a plurality of template holes for pipe-members to extend therethrough, the portions of said template surrounding at least two of said holes being provided with non-circular sockets; pipe-members having non-circular portions fitting 10 said non-circular sockets; and means for securing said non-circular portions in said non-circular sockets.

4. A plumbing fixture comprising: a template designed and adapted to be secured in a building wall or the like, said template having a plurality of template holes for pipe-members to extend therethrough, the portions of said template surrounding at least two of said holes being provided with flared and non-circular sockets; pipe-members having non-circular portions fitting 20 the non-circular portions of said sockets; and means for securing said non-circular portions of said pipe-members in the non-circular portions of said sockets.

JOHN R. O'BRIEN.
